UNITED STATES PATENT OFFICE.

CONRAD HARRIS AND PAUL W. ZOINER, OF CINCINNATI, OHIO.

DESIGN FOR A DINING-ROOM STOVE.

Specification forming part of Design No. 898, dated June 23, 1857.

To all whom it may concern:

Be it known that we, CONRAD HARRIS and PAUL WM. ZOINER, both of Cincinnati, county of Hamilton, State of Ohio, have invented or produced a new and useful Design for a Dining-Room or Oven Parlor-Stove; and we do hereby declare the following to be a full and exact description of the same, reference being had to the annexed drawing, and to the letters of reference marked thereon, in which—

Letter E represents a perspective view of the stove.

What we claim thereon as new, and desire to secure by Letters Patent, is—

The combination and arrangements of the figures, scrolls, and foliage, as set forth in the annexed drawing, forming a new and original design for dining-room or oven parlor-stoves, to be known and called the "Black Swan."

CONRAD HARRIS.

PAUL W. ZOINER.
